UNITED STATES PATENT OFFICE.

HEINRICH HOERLEIN, OF ELBERFELD, GERMANY, ASSIGNOR TO SYNTHETIC PATENTS CO., INC., OF NEW YORK, N. Y., A CORPORATION OF NEW YORK.

PHYSIOLOGICALLY-ACTIVE BASES.

1,178,720.

Specification of Letters Patent.

Patented Apr. 11, 1916.

No Drawing. Original application filed July 22, 1913, Serial No. 780,461. Divided and this application filed October 29, 1915. Serial No. 58,719.

To all whom it may concern:

Be it known that I, HEINRICH HOERLEIN, doctor of philosophy, chemist, citizen of the German Empire, residing at Elberfeld, Germany, have invented new and useful Improvements in Physiologically-Active Bases, of which the following is a specification.

This invention relates to a preparation of physiologically active bases which have valuable properties as a substitute for ergot, or secale preparation; and it comprises a preparation of p-oxyphenyl ethylamin having the formula

15

and betaimidazolylethylamin having the formula

20

made by combining these two bases in an isolated condition or in the form of their salts or by producing them simultaneously or otherwise, the preparation being in the form of mixture of the two bases in powder form or of tablets or pills or of aqueous solutions of their salts, etc., all as more fully 25 hereinafter set forth and as claimed.

This application is a division of application Serial No. 780,461, filed July 22, 1913.

It is known that preparations of ergot, or secale cornutum, as well as various substances or bases isolated therefrom, have a physiological effect upon the uterus and upon the blood vessels, causing their contraction; but the administration of these 35 preparations shows certain disadvantages. Preparation made from ergot or secale cornutum usually contain more or less inert constituents as well as constituents antagonistic to each other in their action. The isolated bases referred to have been experienced with as substitutes for secale preparations but their use in the pure state is accompanied by such after effects as to often render them objectionable. The beta-imidazolylethylamin when employed in therapeutic doses, frequently causes headaches, 40 congestion of the head, erythema over the body and limbs, formication in the arms and legs, nausea, irritation of the conjunctiva, palpitation of the heart, and even

marked cyanosis in consequence of temporary arrest of respiration, convulsions and loss of consciousness (Jaeger, *Centralblatt für Gynäkologie* 1913, No. 8; Kehrer, *Muench. med. Wochenschrift*, No. 33, 1912).

The p-oxyphenylethylamin has the great disadvantage of acting only upon the impregnated and puerperal uterus, but not upon the virginal or quiescent uterus. The physiological effect of both these bases is partly antagonistic and partly synergistic.

The beta-imidazolylethylamin acts as a poison upon the automatic nervous system. It produces convulsions of the bronchial and visceral musculature, inhibition of the cardia action, relaxation of the abdominal vessels, reduction of blood pressure (in cats and humans), fall of temperature, and a tetanizing effect upon the uterus. The last named action is supported by the direct influence of the beta-imidazolylethylamin

upon the unstriped musculature itself, as can be demonstrated on the isolated organ, the uterine contraction being independent of the state in which the uterus may be. On the other hand, p-oxyphenylethylamin has a toxic effect upon the sympathetic nerve. It causes dilation of the pupils and the bronchi, constriction of the blood vessels, increase of blood pressure, and contraction of the pregnant or puerperal uterus, but not of the quiescent uterus. Its action upon this organ is like that of a stimulation of the hypogastric nerve. The remarkable discovery has now been made that by combining both bases, the disagreeable after-effects of the beta-imidazolylethylamin can be greatly diminished or completely neutralized, while the valuable properties of both bases supplement each other, or in the sense of Burgi's law intensify each other, so that a preparation made from these two bases forms a valuable and in many respects superior substitute for secale cornutum or its extracts. This preparation is moreover free from the numerous other substances always present in ergot and which—as is known in the case of opium, digitalis and other vegetable drugs—materially influence the complex action of the natural remedy. The preparation of these two bases, being free from all inert matter and objectionable constituents of the plant, is capable of exact dosage.

2
 The preparation of the present invention acts both upon the virginal and quiescent uterus as well as upon the pregnant and puerperal uterus. This action appears all 5 the more remarkable since, as is well known, the para-oxyphenylethylamin fails to exert any effect upon the virginal and quiescent uterus, and may, indeed, have a relaxing effect, so that in the preparation of both bases 10 an impairment of the contractile action of the beta-imidazolylethylamin was to be feared.

The preparation of the two bases of the present invention may be made in various 15 ways and may exist in various conditions. The two bases may be used in the isolated state in appropriate mixtures, or the bases may be crystallized together in the desired proportions; or salts of the bases may be 20 prepared either separately or in joint crystallization or in aqueous solution.

The bases themselves may be recovered from preparations of ergot or secale cornutum or they may be prepared from histidin 25 and tyrosin by putrefactive fermentation in which case the bases are jointly produced in an economical manner and if desired need not be separated from each other for further use.

The preparation of p-oxyphenylethylamin and beta-imidazolylethylamin of the 30 present invention are intended to be used as substitutes for ergot or secale cornutum, over which, however, they possess very material advantages as already pointed out. The proportions of the two bases which have 35 been found to give the desired physiological action are about 1 part of beta-imidazolylethylamin to about 4-30 parts of p-oxyphenylethylamin. Thus an aqueous solution 40 may be prepared by using 0.1-0.5 parts of beta-imidazolylethylamin-hydrochlorid and 2-3 parts of p-oxyphenylethylamin-hydrochlorid dissolved in 1,000 parts of water.

The preparation of the two bases indicated above in the proportions of 1 part to 45 4-30 parts is a white powder which shows the alkaloidal reaction, *i. e.* gives a precipitate with picric acid and bichlorid of mer-

cury, furnishes azo bodies with diazo compounds, and is very easily soluble in water. 50 Among the salts of the two bases those of greatest importance are the ones most easily soluble in water.

From the hydrochlorids the free bases may be prepared as follows: 1 part of beta-imidazolylethylamin-hydrochlorid and 4 parts of p-oxyphenylethylamin-hydrochlorid are suspended in boiling alcohol and treated while stirring with the calculated amount of sodium ethylate. The separated salt is filtered off and the alcoholic solution of the free bases is neutralized by means of phosphoric acid. After evaporation to dryness, the residue can be used either in the powder form or in the form of tablets or pills, or 60 can be made up into solutions of the desired strength.

The bases may be prepared by subjecting a mixture of histidin and tyrosin to putrefactive fermentation, as already described, 70 and the resulting product or preparation of the two bases may be used in medicine as described above.

The composition of the present invention can be administered by subcutaneous, intra- 75 venous, intramuscular, oral or rectal application.

I claim:

1. As a new medicinal composition, a mixture comprising para-oxyphenylethylamin and beta-imidazolylethylamin characterized by showing the alkaloidal reaction and giving azo bodies with diazo compounds.

2. As a new medicinal composition, a physiologically active preparation of the two bases p-oxyphenylethylamin and beta-imidazolylethylamin in the proportions of about 1 part of beta-imidazolylethylamin to 4-30 parts of p-oxyphenylethylamin.

In testimony whereof I have hereunto set my hand in the presence of two subscribing witnesses.

HEINRICH HOERLEIN. [L. S.]

Witnesses:

ALBERT NUFER,
CLARICE EAGER.
